Application April 6, 1953, Serial No. 346,978

20 Claims. (Cl. 235—61)

This invention relates to improvements in calculating tables, and the like. Generally, the invention has to do with calculating tables which are specially adapted to the solution of problems relating to power generating and distributing systems, including transmission line problems and other problems of like nature. It will appear, however, that various of the features herein disclosed may also be used in calculating tables for other kinds of determinations than those suggested above.

The invention may also be said to relate to improvements in the art of power generation and distribution since the disclosures to be hereinafter set forth relate generally to an improved method of analyzing and determining the conditions of operation of power generating units and the tie lines connecting said units, with the objective of producing and delivering the delivered energy at a minimum unit cost; and the invention further relates to the means to practice said method. More specifically, the invention relates to improvements in such method and in the means to practice the same, whereby the effects of losses in the tie lines connecting the generating units and the loads, and losses in the transmission lines, will be taken into account in making the determinations of operation for production and delivery of the energy at a minimum cost.

At this point we call attention to the fact that the present disclosures may and do apply to use in making determinations in the case of multi-unit power generating and delivering systems, whether the several units of such multi-unit system be housed under a single roof or comprise a single group, and wherein the units are connected by tie lines such as bus bars or other ties, such as transformers and connecting lines, and constitute a single power station, or whether the several units be distantly separated from each other but connected by transmission or other tie lines. The features of the present invention are usable to effect the desired determinations, or to facilitate the making of such determinations, with accuracy and expedition in either of the general classes of problems outlined above. In all cases, however, proper account is or may be taken of the losses in the tie lines, transmission lines, and other network elements interposed between the generating units and the points at which energy is delivered, and interposed between various generating or supplying units. These losses will be much smaller in the case of the tie lines or elements connecting the generating units of a single power station than will be the losses in tie lines and network lines and elements, especially when the several generating stations or supplying units are located distant from each other, but in principle the effects of the tie line and other losses are the same in both categories of cases. The differences are primarily of degree, not kind.

It is well known that when a demand for delivery of a stated amount of power at a given point is to be satisfied by supply from two or more generating or supplying units, the determination of the most economical division of the demanded power as between said units must take into account the forms and the values of the input-output

2

curves of the several generating or supplying units in question, and must take into account the forms and the values of the incremental rate curves based on said input-output curves for said units. The input-output curve for each unit shows the variation of input (whether in fuel or stated in dollars per unit power or energy) needed to satisfy varying output demands over the power range covered by the curve. The incremental rate curve shows the rate of variation of the input-output curve as the output is varied. Thus, the incremental rate curve shows the amount by which the increments of input must change as the output is successively changed by equal increments of output.

It is well known that when two or more generating or supplying units are acting to satisfy the demand, the most economical division of the total demand between said units will be that division in which all of the supplying units are operated at loads such that all of the units are operated at equal incremental rates. That is, for the most economical division of the total demand, all of the supplying units should be operated at the same incremental rate conditions (disregarding for the time being losses in the lines connecting said supplying units). When the total demand for power changes the new total power value should be re-divided between all of the supplying units in such a way that all of said units are again (or still) operating at equal incremental rate conditions and loadings. These new incremental rates may or may not be the same as those existing prior to the change of total power demand. This is true, disregarding for the time being the losses before referred to.

The practical effect of the above statement is that the most economical total power output is obtained when each of the power contributing units is operating at such a load that throughout a minute change of its proportionate contributed power the cost rate of its contributed power will be the same as the cost rate of each of the other contributing units when their respective contributed loads are also changed by proportionate minute amounts.

40 The foregoing statement disregards the effects of losses, as already explained.

The truth of the foregoing statements is evidenced by proper mathematical analysis and is well known, and we shall hereinafter make reference to published works showing the mathematical derivation of the above conclusions. In applying the above stated principles to any specific set of units, proper account must be taken of any conditions of "discontinuity" in the curves of incremental rates plotted against outputs, for the several contributing units under consideration. Also, the curves of incremental rates for the several contributing units are conveniently plotted on a cost or dollars and cents basis so that the final results of the analysis shall reveal the operating conditions which will enable delivery of energy at the delivery point or points at a minimum total or overall cost in dollars. Furthermore, the incremental rate curves for the several units must in any case be based on certain underlying assumptions, and they may show delivered cost increments at the bus bars or the generator terminals or elsewhere. In any case such curves should represent determinations of incremental costs including all proper elements of such costs from the coal (or other fuel supply) to the assumed point of energy delivery for the respective generating or supplying units.

When more than one supplying unit feeds power into the system, said units are tied together within the generating station by bus bars, switches, transformers, and other elements. Energy losses will occur in these tie elements and these losses will necessarily affect the cost of energy delivered to the system being fed. Frequently

these tie losses which are internal to a generating or supplying station are small as compared to other losses affecting the overall cost of the delivered energy. In such cases said losses may be disregarded without seriously affecting the accuracy of the solution of the problem of determination of the most economical division of the assumed total load among the various contributing units. In other cases these tie losses which are internal to the generating or supplying station may be of such amounts as to seriously affect the correctness of the analysis on which the division of the total power between the units is based. Such errors may materially affect the total cost of the useful energy delivered by the station due to division of the power between the several contributing units in a manner which is not the most economical.

We shall presently consider the effects of the tie and other network or line or like losses on the solution of the problem of effecting the most economical division of the demanded power among the contributing units, and shall disclose a method and the means which we have devised for including said losses in the determinations of division of power between the contributing units so as to ensure delivery of the useful energy to the delivery points at a minimum total cost per unit energy. Said method and said means may be usefully applied whether the contributing units be located close together, as under a common roof, comprising a single generating station with its units feeding into common bus bars, in which case the effects of the losses occurring in said bus bars and in any connecting transformers will be properly included in the solution of the problem; or whether said contributing units comprise separate steam driven generating units with separate transformers individual to said generating units with ties connecting the outgoing lines; or whether the contributing units be located distant from each other. In cases where all of the contributing units are located close together and comprise in effect a single power station, the tie losses occurring within such station may be included in making the determinations of best divisions of load as between the units of such complete station, and incremental cost curves for such entire station may then be made based on such best conditions of operation of the units of such station as an entity. These incremental cost curves may then be used in connection with further determinations of division of load between several stations feeding into the complete network in order to determine the conditions of operation which will ensure most economical delivery of the total load to the points of use. The losses occurring within the station itself above referred to may be conveniently termed "internal losses" and the losses occurring outside of the contributing stations may be conveniently termed "external" or "network" or "line" losses.

We have already shown that, when the losses are disregarded the several units contributing to the total demanded power should be so operated that their incremental rates are the same, in order to ensure delivery of the total energy most economically. This is also true in the case of contributing stations distant from each other, when the losses are disregarded. However, the network and line losses may and generally will be considerable and constitute a considerable portion of the energy delivered by the contributing stations or units. These losses constitute an additional load which must be carried by the contributing stations. Accordingly, this "loss" load will require that all of the contributing stations together be loaded by an amount equal to the delivered load plus this loss load in order to deliver the specified useful or delivered load. However, it does not necessarily follow that this additional "loss" load will be carried by the several contributing units proportionately to the most economical loads which they should carry. This is true since the manner in which this loss load will be distributed over the network will depend on many

5 factors determining such distribution. Accordingly the principle already referred to of equality of incremental rates of the several power contributing units in order to ensure most economical delivery of the useful power must be modified in proper manner in order to take care of the effects of the losses occurring in the connecting lines and other connecting elements. We shall presently show how such modifications are to be made, and shall disclose the means which we have disclosed herein to 10 facilitate the determination of the exact division of power between the contributing units in order to ensure the most economical or lowest cost delivery of the useful energy to the delivery points.

15 The above relationships have been known and analyzed mathematically in published explorations including the following:

28 "Evaluation of methods of co-ordinating incremental fuel costs and incremental transmission losses" by L. K. Kirchmayer and G. W. Stagg, A. I. E. E. Technical Paper 52-112, January 1952, pages 1-10 and accompanying tables and figures.

33 The mathematical determinations and solutions of the optimum loading conditions for the elements of any given generating plant are necessarily based on some assumptions and, where necessary, on suitable test performance data for the various elements and units of such plant, assumed fuel costs, etc. Primarily such assumptions and test performance data are necessary to determine and plot input-output curves and incremental rate curves for the various units of each generating station or other supplying unit. Performance data of various elements, such as transformers, etc., affecting incremental transmission losses may be secured either from the manufacturers of such elements or by empirical tests.

38 With the necessary test and other performance data 40 at hand the mathematical solution of the theoretically correct division of the total network load between the several contributing units feeding the network, for the most economical overall conditions of operation is very involved and laborious and time consuming. Even so, 45 the solutions thus evolved are usually based on certain simplifying assumptions, and corresponding errors may be expected to creep into the mathematical solutions. Such schemes have also included various cut and try operations, and in some cases network analyzers have been 50 used to simplify the operations. All of these previously known means of solution of the extremely involved problems presented by the network and line losses have been 55 so complex, or have involved such time consuming operations, and possibilities of error, that they have found 60 but limited application to the real problems presented in the operations of power generation and distribution systems.

65 Specially, one feature of our invention includes means comprising a special type of network analyzer or calculating board by which the power losses occurring in the various network elements which are simulated by the calculating board may be directly read on a suitable instrument or instruments such as a voltmeter or voltmeters. The arrangement is such that said instruments may be caused to read directly in power loss such as megawatts, not-

withstanding that said losses are for the most part a squared function of the line current values (being principally resistance losses).

The loss in each line element of the network may be individually determined by the disclosures above referred to. A further feature of the invention relates to the provision of means whereby the losses occurring in any selected group (or all) of the line elements may be shown by a single reading of the same instrument as is used for showing the individual losses of the various line elements or network elements; or another and special summarizing instrument may be used for showing the desired summation. Provision is made in the calculating board for quickly connecting the power loss indicating instrument or instruments to those selected line elements or groups of line elements concerning which it is desired to know the power losses under various loading and load division conditions. Thus it is possible to make very quick determinations of said power losses by direct readings of the instrument or instruments, and to make such determinations for any given set of stable conditions of network operation, or to determine and show how the power losses vary under regularly varied conditions of loading, etc., at different network locations, or for varying selected conditions of division of total load delivered by the contributing supplying units.

The calculating board is provided with suitable line and other element simulating elements or sections. Each of these preferably and conveniently includes means to simulate both the resistance and inductance (or capacitance) values of the real network element being simulated. Both the resistance simulating element and the inductive (or capacitive) simulating element for each real network simulating section may be adjustable through the necessary range of values to simulate the real values of the corresponding real network elements.

The loss in each real network element is primarily a function of the current flowing in said element and is a resistance loss. As such, the resistance loss is a squared function of the current value. In the case of such an element as a transformer included in a network section to be simulated or as an element thereof itself, the resistance loss occurring in such transformer will also vary as a squared function of the current; the iron losses may be disregarded as they are substantially constant and may be ignored in solving for the most economical division of load between the stations.

In order to determine the loss in the real network element it is therefore necessary to provide means in the simulating network element which corresponds to said real network element by which the loss occurring in the real network element as a squared function of the current, may be simulated. We have also provided each simulating network section with the means to simulate the resistance and the reactance already referred to; it being understood that thereby provision has been made in the simulating network section to simulate the resistance drop occurring in the real network, the reactance effects, and the loss, this latter function being indicated or shown specially. This loss indicating element of the simulating network includes a special resistance element, presently to be referred to, and which special resistance element is supplemental to the resistance element previously referred to, which simulates the resistance of the real network element.

Although the resistance loss is a squared function of the current flow in the network element in question, the means for indicating this loss is such, and is so arranged, that the indicated loss shall be according to a linear function of the actual loss. It will be indicated as a D. C. voltage appearing across a pair of terminals. The conversion from the condition of a loss whose value is a squared function of the current, to an indication in the form of a D. C. voltage across a pair of terminals, is very important to the performance of the objectives and

the functions to be herein disclosed. For example, by the use of such linearity of indication, and especially when the indications are given as voltages appearing at the terminals which correspond to the simulated real network elements, it is possible to immediately and at a single operation show the additive losses of a number of selected network elements, or all of the network elements of an entire system. This result can be and is obtained in our present disclosures by providing the means to connect into a series circuit all of the voltage indicating terminals of the simulating network elements of which the summed loss is to be ascertained. Then the total voltage from such series circuit will be an indication of the total loss occurring in all of said simulated network elements under the conditions of current flow then existing. The change of total loss in the group of network elements (or in all of the network elements) whose voltage indicating terminals are at the time connected into such series, which change of total loss accompanies a re-division of the supply of power from the several contributing power units, may be at once ascertained from the new reading of such loss as compared to the loss indicated by the previous reading for the previous conditions of division of power supply.

The ability to thus bring all of the "network element loss indicating voltages" of a group of the simulating elements into a single additive reading or indication is also dependent on the electrical separation of the circuits which give the loss indications, from the simulating network elements themselves. We have provided means and arrangements whereby this result is obtained. The need and importance of this characteristic will be seen when it is remembered that the additive A. C. voltages appearing across a number or group of simulating network elements, which voltages simulate the impedance drops across said elements, do not necessarily, and in fact almost invariably do not, bear any direct relation to the additive D. C. voltages indicating losses occurring in the network elements referred to.

The means whereby the loss in each network element is shown as a D. C. voltage reading varying linearly with loss at a pair of terminals includes a special non-inductive resistance element included in the simulating section of the miniature network, and through which special resistance element substantially all of the current of the miniature network section flows. The A. C. drop across this special resistance is then used to function a local circuit of such nature and characteristics that the desired linear power-loss-measuring voltage indication will appear at the terminals of such local circuit. Since this special resistance acts as a portion of the total resistance of the simulating network section, the other resistance element of such section must be adjusted to a value such that the sum of the resistances of such special resistance element and such other resistance element will correspond to and simulate the actual resistance of the real network element which such section simulates. We have made provision for effecting such correction in setting up the simulating elements of the miniature network section.

We have above referred to the special resistance element which comprises a portion of the means to determine the loss in the network section. The drop across this special resistance element will be proportional to the current which it carries. Therefore said drop would be considerably larger when carrying a large current (such as when said section simulated a heavily loaded real network element) than when carrying a small current (as when said section simulated a lightly loaded real network element). Now the local circuit by which the current flowing in such special resistance element is caused to deliver a D. C. voltage across a pair of terminals, which D. C. voltage is linearly related to the squared functional loss occurring in the network section, includes special devices which have a peculiar current vs. voltage

characteristic or relation. This characteristic is that the D. C. voltage output from such a device varies as a non-linear function of the A. C. current flowing to such device. But this relationship is only true over a comparatively limited range of current values (for a given such device). Among such devices having this desired characteristic is a class of devices known in the electrical arts as "varistors." Among these are some which include the elemental material germanium, and also some crystal diodes made by Sylvania Electrical Products Corporation.

The above relationship which we have mentioned as being non-linear is one in which, for small values of E and I the relationship is of the order of a geometrical function greater than the squared function. Then, as the value of E is increased the relationship becomes a squared relationship for a further range of variations of E , and for still higher values of E the relationship approaches linearity. We have provided means whereby we are able to ensure operation according to the squared law function over a range of D. C. voltage outputs sufficient to meet all requirements of the device as used in our present disclosures.

The above explanation concerns the means which we have provided to indicate and measure the losses which occur in the individual network elements, or in selected groups or all of said elements. These losses must be supplied by the several power generating or supplying sources feeding into the network. It now remains to show the means which we have provided to enable us to determine the division of the total power fed into the network between the several contributing units in such manner as to ensure the most economical supply of said total power from such contributing units. At this point it must be remembered that the total supplied power includes both the power delivered to the consuming units connected to the network (the useful delivered power), and also the losses occurring throughout the network itself. It must also be noted that said total losses are distributed over the network sections or units according to the resistances or impedances of said elements and the loads which they severally carry when the various delivered loads are drawing power from their respective points of connection into the network. It is also and at once apparent that the distribution of the currents through the network will depend upon the manner in which the total load (including the losses) is divided among the several contributing units themselves, and that any shift or readjustment of the total power between the several contributing units is immediately accompanied by a redistribution of the current flows through the various network elements. This in itself will cause many changes to occur in the values of the losses occurring in the network elements so that a redistribution and re-evaluation of said losses over the entire network will occur. These changes may of themselves, and generally will, result in either an increase or a decrease of the total losses, with accompanying change in the total power which must be fed into the network to supply both the useful load and the losses. This change in total required power supply or input will of itself call for a redistribution or re-division of the total power between the contributing units. Thus, each change of one kind requires a correctional change to be made at various points of the system, in order to finally arrive at a balance of conditions which shall represent the desired solution of the problem. In the case of a complex network, having many loads receiving power, and of various load values, and having many network elements, and a number of generating or supplying units contributing to the network, a great many tests and readjustments would almost invariably be required before even a close approximation to the desired conditions could be attained. Of course that approximation, as exact as can possibly be obtained, is the determination of the manner in which the several contributing power supply units shall divide the total

power between them for ensuring maximum economy of overall operation.

However, we shall presently show how the necessary determination of the division of total power (including the losses) between the several contributing power contributors may be quickly and accurately determined by use of the facilities which we have previously outlined herein.

Here it may be noted that all of the facilities and the methods of solution of the problem of determining the most economical division of load between a plurality of power supplying units when the effects of the losses are to be included in the determination, are applicable to the case of a multi-unit generating station in which tie lines, tie transformers, bus bars, and other power loss creating elements are present. We have made reference to this fact hereinbefore. Accordingly, when desired or justified, the methods and facilities hereinbefore outlined may be applied to the solutions of problems involving determination of incremental rates (of an entire power station) to plot the curve of incremental costs or rates of delivered energy for an entire supplying station. In such case the useful load or loads would be the points of delivery of the energy to the transmission line or lines, or the point of connection into the network being supplied by such station.

We have provided means to measure the power input from each contributing station into the network, so that the several powers contributed by the stations may be measured. Such means takes the form of suitable wattmeters included in the connections of the stations to the network, or a wattmeter which may be successively switched into the connection of each contributing station to the network. The determination of the most economical division of load between the several contributing stations, with proper account taken of the effects of the line losses, requires a determination of the effects produced by small or incremental changes in the powers supplied by the several stations. These incremental changes in supplied power are of small values compared to the actual power inputs themselves, of the order of 5% of the respective power inputs from the several stations. The accuracy of a determination of the most economical division of power between the contributors requires that these power increments be themselves accurate within small percentages of such incremental values. Thus, if the incremental change of power of any station should be known within an accuracy of 5% of such incremental change, the actual power change to be thus accurately determined would be of the order of 0.25% of the total supplied power, a very small change of total power determination. Nevertheless it is important that these incremental power changes be accurately known in order to effect accurate determinations of the final solution of the problem of most economical division of power between the contributing stations.

An important feature of our present invention relates to the provision of an incremental power or wattmeter which shall be capable of indicating the increments of power change with a high degree of accuracy. Such an instrument is hereinafter disclosed and illustrated herein.

When it is desired to determine the values of incremental losses occurring in the network elements or certain of said elements, the differences in voltage readings of the loss indicating voltmeter may be used for this purpose; but since these incremental changes in value of the losses will be very small as compared to the total losses indicated, it is seen that accuracy of determination of the incremental changes may require special provision to enable such incremental change values to be made. Accordingly we have made provision for determining the incremental loss changes which are to be determined, within a small percentage of error of such incremental values.

In the drawings:

Figure 1 shows typically the relation between input and output for a typical generating station or plant (plant *a*) and also shows the corresponding incremental rate curve for said plant, both of these curves being determined according to well known and understood principles and tests;

Figure 2 shows typically the three incremental rate curves for three plants of assumed characteristics (including the incremental rate curve for plant *a*, which curve is taken from Figure 1), the curves of Figure 2 being all drawn on the same scale for ready comparison of the incremental rates under various test conditions;

Figure 3 shows schematically a simple calculating board and its sections, under the conditions of a set-up for power input by three contributors, and 11 points of delivery of load from said network; and this figure also shows schematically the series circuit for providing a summation of the individual losses of the several network sections extending substantially parallel to the various network sections for convenience of schematic showing;

Figure 4 shows schematically more in detail a typical simulating network section, including the variable main resistance, the variable reactance, the variable special resistance used for actuating the local loss determining circuit, and said local loss determining circuit, and one form of local loss determining circuit shown schematically according to simple form, and including varistors as rectifiers and in order to secure the desired conversion from the squared relation to the linear condition of loss indications;

Figure 5 shows typically the characteristic curve of relation between current and voltage for a varistor included in the rectifying portion of the circuit shown in Figure 4; and the curve of Figure 5 shows how said relation between current value and voltage drop across the varistor is according to a non-linear relationship over a limited range of current (and voltage) values, but approaches linearity for higher values of said functions; and this curve also shows that it is desirable to retain the conversion operations or effects of the local circuit within the non-linear relation portion of this curve;

Figure 6 shows schematically how the local loss determining circuits of a number of simulating network sections may be connected into a summarizing loss determining circuit for showing simultaneously the combined losses of all or selected simulating network sections, by addition of the several loss indicating voltages of the sections; and this figure also shows means, local to each of the local circuits for adjusting the per unit value of the loss indications indicated by the voltages appearing at the terminals of such local circuit; and this figure also shows additional means to enable the use of a multirange voltmeter in connection with the series loss indicating circuit to enable summation of the losses of many selected simulating network sections from which the additive value of the loss indicating voltages would be so large as to make it desirable to use a higher range voltmeter than for readings of voltage indicating losses under other test conditions, the arrangement shown in Figure 6 including a simple changeover circuit and switch to enable use of the voltmeter of either of its ranges of readings;

Figure 7 shows schematically a modified form of one of the rectifier sections of the unit "70" shown in Figure 4, by the use of which modified form of rectifier section it is possible to secure the delivered D. C. potential according to the squared law over an increased range of applied A. C. potentials applied to the points 68 and 69 of said Figure 4, it being understood that the section shown in Figure 7 is one of the four sections shown in Figure 4, and that in making the substitution of the form of Figure 7 into the showing of Figure 4 each of the sections or rectifiers shown at 80, 81, 82 and 83 shall be of the form shown in Figure 7; and

Figure 8 shows schematically a form of incremental

load wattmeter suitable for use in measuring the power supplied to each of the points of power supply into the network, it being understood that each of the wattmeters shown at 102, 103 and 104 in Figure 3 may be of the type shown in Figure 8.

The features of our present invention are applicable to various forms of calculating tables and like devices, and the present improvements are especially intended for use in connection with alternating current calculating tables. Various forms of such calculating tables are well known in this art, including, by way of example, those shown in Patents Nos. 2,523,453, issued to James H. Starr September 26, 1950, and 2,613,237, issued to James H. Starr October 7, 1952. It is unnecessary to illustrate and describe herein the full details of a calculating board incorporating the improvements of our present invention, and accordingly we have herein shown said improvements more or less schematically as applied to a simple form of calculating board. However, we have also shown in more detail the essential elements of one simulating network section incorporating our present improvements for full understanding of said improvements. Before referring to said schematic calculating board showings, however, we shall first refer to Figures 1 and 2 showing the general forms of the input-output and incremental rate curves previously referred to herein, for better understanding of our improvements.

In Figure 1 the output and input values are shown by the horizontal and vertical readings, respectively; and the incremental rate values are shown by vertical values. The curve 20 shows the relation of input to output over the range of loadings covered by the chart. The ratio of increment of input for each increment of output is the incremental rate for the output in question and may be expressed as di/do . This ratio also is a measure of the slant of the curve 20 at any selected point. The curve 21, on the foregoing basis, is the incremental rate curve for the unit of which Figure 1 shows the characteristics. We are here especially concerned with the values and operational characteristics supplied by the incremental rates, such as shown by curve 21. The values shown by such incremental rate curves may be given as incremental costs of delivered energy or power for assumed fuel costs, and assumed operating costs of the unit or plant for which a given incremental rate curve is representative. This is a convenient manner of developing such incremental rate curves, as thereby the determinations may be made both on a comparative basis and also on an absolute cost basis.

It will also be evident that when a given generating station or contributor contains a number of power supplying units there may be developed a combined curve of incremental rates, representing the overall per unit cost of energy delivered by such plant to the transmission lines, taking account of all of the cost factors involved in the production of the energy and properly to be considered in developing such plant curve. In developing such a plant incremental rate curve use may be made of the improvements herein disclosed in order to take account of the effects of losses when such effects are appreciable, and when a high degree of accuracy and reliability of the final results is desired. We have previously referred to this fact.

In Figure 2, presently to be considered more in detail, we have brought the incremental rate curves for three typical contributing plants together on a single chart, and on the same scale of values, for purposes of convenience in reference of the incremental rates of the several plants to each other and to the loads carried by the several plants. These are the curves 22, 23 and 24 for the plants *a*, *b* and *c*, respectively. These incremental rate curves are purposely shown as non-parallel, and of widely different rate values for stated loads.

Now, when the losses are disregarded the best and

most economical division of the total load between the plants *a*, *b*, and *c* would be that in which the incremental rates for all three of these plants, as shown by curves 22, 23 and 24 were equal. For example, if the total load to be divided were substantially 193.5 megawatts, that total could be obtained by the loading the three plants to the loads shown by the line 25, since that line intersects the three lines 22, 23 and 24 at the loads of 57.5 mw., 64.0 mw., and 72.0 mw., respectively, the combined total of these three plant loads being the desired total of 193.5 mw. For a shift of the desired or specified total to another value, the several contributions could be readily determined by shifting the line 25 either up or down to the position where the new total value would be produced by the summation of the three points of intersection of such line 25 at its new position, with the three curves 22, 23 and 24.

We have already shown that the inclusion of the effects of the losses in determining the division of the loads may be very important to actual operation under the most economical operating conditions. We have also shown that it can be mathematically demonstrated that the total network losses have a definite mathematical effect on the solution of the problem of most economical division when the effects of losses are to be included in the determinations.

In Figure 3 we have shown, schematically a simple network supplied by the three stations *a*, *b*, and *c*, numbered as 26, 27 and 28, respectively in said figure. The network illustrated includes the network sections 29 to 45, inclusive, feeding the loads 46 to 56, respectively. The general arrangements of simulating networks of miniature size are well known, and therefore we do not herein show in detail the various sockets and plugs, and other detailed devices by which the network may be set up to simulate, in its connection, the connections of the real network. It will also be understood that suitable ammeters, voltmeters, and other elements or units are provided for measuring the desired current flows, voltages, etc., at various points of the set-up of the miniature simulating network, and that the necessary ground and return connections are provided in the calculating table to complete the circuits.

Furthermore, each of the network sections 29 to 45, inclusive may be of convenient form and arrangement, provided it complies with the requirements hereinbefore stated, and incorporates the needed provisions for determining and indicating the loss occurring in such section.

In Figure 4 we have shown schematically one simulating network section meeting the requirements of the present problem. In this case we have shown the main resistance element 57 which is adjustable through the required range of values by the movable contact 58; the variable and adjustable inductance (or capacitance) 59, and the special resistance element (non-conductive), 60 connected in series relationship. This special resistance element 60 is also adjustable as to value as shown by the arrow. The terminals of the section are shown at 61 and 62, and the current flowing through this section simulates the current flowing through the corresponding section of the real network being simulated.

The section also includes a small transformer 63 whose primary 64 is connected to the terminals of the special resistance 60 so that the potential imposed on this primary is equal to the drop occurring over the special resistance 60 at the adjusted value of said resistance. This transformer is of such small size and design that its primary current (substantially only a magnetizing current) is so small in comparison to the current flow through the resistance 60 that, for all practical purposes the current through said special resistance is the same as that flowing through the section of the simulating network. Thus, the drop imposed on the transformer primary is substantially proportional to the current through the network section. Accordingly the delivered potential of the trans-

former secondary 65 is also substantially proportional to the current flowing through the simulating network section. This is, of course an alternating potential.

The terminals 66 and 67 of the transformer secondary 65 connect to the two diagonally opposite points 68 and 69 of the rectifier unit 70, and the intermediate points of this rectifier unit, 71 and 72 deliver rectified current to the lines 73 and 74. The potential of this rectified current will pulsate, since it corresponds to the rectified half-waves of the potential delivered over the lines 66 and 67 from the transformer secondary. In order to largely eliminate these pulsations, and to deliver a relatively smooth delivered potential, we have shown the capacitor 75 bridged across the lines 73 and 74. With this arrangement a substantially smooth potential and current will be delivered beyond the capacitor. The lines 73 and 74 connect to the terminals of a potentiometer 76 which must absorb the entire potential coming over said lines 73 and 74. We have provided the adjustable contact 77 on this potentiometer so that the delivered voltage at the terminals 78 and 79 will be proportionate to the voltage delivered over the lines 73 and 74, as modified by the potentiometer setting.

The rectifier unit 70 includes the rectifying elements 80, 81, 82 and 83 which are one-way current flow elements. These elements are such as to possess the peculiar characteristic to which we have previously referred herein, namely, that the permissible current flow through them is not a linear function of the potential to which they are subjected, over the range of current values needed for the present purposes. We will presently disclose herein a modified arrangement of elements whereby the range of current values within which the squared function will obtain may be substantially increased to meet whatever range of said values may be needed to meet the requirements of the present combinations of elements and uses thereof.

In Figure 5 we have shown a typical characteristic of one such device as those shown at 80, 81, 82 and 83, by the curve 84 showing variation of current flow permitted through the device for varying potentials imposed across its terminals. It will be seen that over a portion of the range of current variation the curve 84 is non-linear, and that over a small portion of this curve between the potential values of 1 and 4 (on the arbitrary scale of Figure 5), the current varies substantially according to the relation that the current value is proportional to the squared value of the potential imposed across the element. For potentials less than 1 (on said arbitrary scale), the relationship above referred to is of an order higher than the squared relation. For potential values higher than substantially 4 (on said arbitrary scale) the curve approaches linearity, as shown by the dashed portion 84^a of said curve. Such devices are included in the term "varistors," and we have previously mentioned certain of them which are readily obtainable. Others are also useful for the present purposes. The essential characteristic of such devices as used in the rectifying circuit is that the voltage delivered at the terminals 78, 79 shall vary according to the square law relation, as already explained.

With such a rectifying device included in the circuit arrangements the following operations will obtain:

The drop across the special resistance 60 is substantially proportional to the current flowing through the network section. The potential developed across the secondary terminals of the transformer is therefore also proportional to the value of the current flow through the network section. But the loss occurring in the network section is proportional to the squared function of the current flowing through that section. Accordingly it is needful that the linearly proportional A. C. potential across the transformer secondary lines 66 and 67 be converted into a D. C. voltage across the terminals 78 and 79 which voltage shall be proportional to the square of the value of the current flow through the resistance 60,

and therefore proportional to the square of the value of the A. C. potential delivered between the lines 66 and 67. Although the potential delivered at the terminals 71 and 72 of the rectifying unit 70 is a rectified potential, the permissible value of current flow permitted by the rectifying unit through such unit must be according to the characteristics of the local circuit of Figure 4, including the characteristics of the rectifying elements 80, 81, 82 and 83. This current flows through the resistance of the potentiometer 76, so the D. C. voltage which will be developed across that potentiometer must be proportional to the above mentioned current value. Therefore as the D. C. potential across the terminals 71 and 72 of the unit 70 varies, the D. C. current flowing through the resistance 76 will also vary, but according to the requirements that the relation defined by the square law previously referred to shall obtain.

In Figure 6 we have shown four of the voltage and loss indicating elements such as just described, but brought into a series circuit arrangement to integrate the several loss measuring indications for the four network sections. These sections are shown at 85^a, 85^b, 85^c and 85^d, respectively. The terminals for the loss indicating voltages of these four elements are shown at 78^a and 79^a, 78^b and 79^b, 78^c and 79^c, and 78^d and 79^d, respectively. These several terminals are suitably connected into the series circuit shown. The loss indicating voltmeter 89 is of suitable design and is provided with suitable scales, to read losses in values convenient for the conduct of the intended operations. Conveniently this voltmeter is a multiscale, vacuum tube instrument, having two or three scales in comparison to which the pointer may be read, and suitable internal switching arrangements, so that the instrument may be used for several different voltage ranges, to enable use of the same instrument over a wide range of losses. Conveniently also, additional range enabling facilities may be provided as shown in Figure 6. In this case we have shown the two throw, two pole switch 90, with the two pairs of stationary contacts 91 and 92, and 93 and 94, the switch blades being designated 95 and 96. The contacts 91 and 92 are connected by the jumper 97. A potentiometer element 98 may be tied across a suitable D. C. supply, such as the battery 99 by closing the switch 100. The movable contact 101 enables securing any desired value of "bucking" potential between the stationary terminals 93 and 94, the connections being properly made so that when the switch 95 is thrown to engage said terminals 93 and 94 the voltage as adjusted by the setting of the contact 101 will buck the accumulated voltage delivered by all of the loss indicating elements of the network then connected into the poss testing local circuit. By this means a single voltmeter may be used to measure small incremental voltages, i. e., such as a few percent of the total.

It is also noted that the foregoing or equivalent arrangement makes it possible to bring the amount of the "bucking" voltage to a value such that the totalized sum of all of the loss voltages in the series circuit is neutralized. When this is done the net voltage shown by the instrument 89 will be zero, the instrument having been brought to a "suppressed zero" position. Having done this, any change in the network system which produces a change in the total amount of the losses, can be read as a direct reading of the instrument 89, and without need of subtracting one reading from another. Thus the instrument under such suppressed zero setting becomes a direct reading "incremental loss" meter. Without further change of the instrument the incremental losses would then be read on the same scale of said instrument as would be used for reading the total losses. Such a scale, covering a considerable range of voltages as needed for indicating the total loss, would be difficult to read accurately for the small incremental loss voltage indications. Furthermore, such small incremental losses could not be accurately indicated on the instrument without change of

instrument characteristics. We have made provision for change of the instrument characteristics as follows:

The instrument 89 may normally be used for the total loss voltages, which are shown by reading the position of the pointer 89^a on the high range scale 89^b. By depressing the button 89^c the characteristics of the instrument are changed so that it becomes a low range instrument and continues as such low range instrument as long as the button 89^c is depressed. During such low range condition the voltage of small amount will be accurately shown by the position of the pointer 89^a on the scale 89^a, the full range of which scale corresponds to a small voltage as compared to the full range of the scale 89^b. When the button is released the instrument characteristics are again restored to the high voltage range characteristics.

Using the foregoing instrument 89, or equivalent device, when the bucking voltage has been adjusted to set the instrument reading back to zero (by full bucking) so as to suppress the zero reading, the instrument button 89^c may be depressed so as to bring into use the low voltage elements of the instrument. While said button is depressed the incremental change in power supplied to the network by one of the contributors 26, 27 or 28, as shown by the corresponding instrument 102, 103 or 104, may be determined, and at the same time the incremental loss corresponding to such incremental power supply may be noted on the instrument 89. Such incremental loss may thus be very accurately determined, corresponding to the incremental power indication of the instrument 102, 103 or 104 (or a modified form of "incremental wattmeter" presently to be disclosed herein, or equivalent device). Both incremental power and incremental loss may thus be very accurately determined.

The accurate incremental data, both of power supply and of losses, may be used for various determinations, some of which have been previously referred to herein.

The indicating wattmeters 102, 103 and 104 shown in Figure 3 are included in the supply leads connecting the contributing stations 26, 27 and 28 to the network. Some of the uses and functions of these wattmeters have already been disclosed herein. We will presently disclose one special form of such wattmeters, which we term "incremental wattmeters," and which are so arranged and designed that very small incremental power measurements may be made by them with a high degree of accuracy. We have already referred to the desirability of provision of such accurate wattmeters in connection with the present equipment.

Referring to Figure 7 we have therein shown schematically a modified form of rectifier element which may be substituted for each of the elements 80, 81, 82 and 83 of the unit 70 of Figure 4. By way of simplicity of description we shall refer to this element of Figure 7 as being in substitution for the element 80 of Figure 4, and shall describe its characteristics and connections on that assumption; but in so doing it will be understood that other elements similar to that of Figure 7 will likewise be substituted for the elements 81, 82 and 83, and with their terminals properly connected into the network "70" to ensure properly related rectifying effects for the currents delivered to the terminals 71 and 72 of said unit 70.

The unit shown in Figure 7 and theredesignated in its entirety by the numeral 105 includes one or more "varistors" 106 connected in series across the elemental terminals 107 and 108. When the element 105 is substituted for the element 80 of Figure 4 these terminals 107 and 108 connect to the points 71 and 68 of the unit 70 of Figure 4; other elements like that of Figure 7 would also be connected with their terminals 107 and 108 connected respectively as follows; element 105 substituted for element 81 would have its terminals 107 and 108 connected to the terminals 71 and 69, respectively; element 105 substituted for element 82 would have its

terminals 107 and 108 connected to the terminals 68 and 72, respectively; and element 105 substituted for the element 83 would have its terminals 107 and 108 connected to the terminals 69 and 72, respectively.

In Figure 7 we have shown three of the varistors 106 connected in series and designated 106^a, 106^b and 106^c, respectively. A greater or less number of these varistors will be used as required by the particular installation, and depending on the characteristics of the varistors themselves. When the varistors 106 are all of like characteristics to a close tolerance it will be evident that the total potential applied between the terminals 107 and 108 will be equally divided between all said varistors (in the showing of Figure 7 each varistor being subjected to one-third such potential). Accordingly, the voltage range or variation which must be taken care of by each such varistor will be only one-third of the total applied potential. Thus, too, each such varistor will operate on a much more limited portion of the curve 84 of Figure 5 than would otherwise be the case. By this means it is possible to bring the varistor operations into a portion of the curve 84 which will be of form substantially meeting the requirements of the square law.

However, we have made still further provision for bringing the operations into the square law relation, as follows:

Another varistor (or series of varistors) 109 is also connected between the terminals 107 and 108 by the connections 110 and 111, such varistor 109 being properly connected with respect to the varistors 106 so that it permits current flow between the terminals 107 and 108 in the same direction as the varistors 106. Such fact is evidenced by the pointing of the arrows at the locations of the several varistors. Thus we have provided two parallel paths for the current flow between the terminals 107 and 108, one path including a plurality of the varistors in series, the other path including one or more other varistors, also in series with each other but in parallel with the first group. We have also provided the resistor 112 in series with the varistor (or varistors) 109, so that the current flow through the left-hand branch of the circuit is affected by the presence of this resistor 112. If desired this resistor 112 may be adjustable as shown by the arrow 113 of Figure 7.

By the use of the combination shown in Figure 7, or such variations thereof as may be found desirable, as to number of varistors, etc., it is found possible to assure operation according to the requirements of the square law over a wide range of applied voltages, and completely sufficient to meet all requirements of the operations herein contemplated, and with an accuracy of a few percent error through the required range of operations.

It is also to be noted that although the unit shown in Figure 4 by the numeral 70, and also such unit as modified by the disclosures of Figure 7 is a full wave rectifying unit, still it is completely possible to use half-wave rectifying units for the purposes of our present disclosures, provided that the square law to which we have referred, is applicable and operates at all times during the rectifying operations, so that the desired and intended results are obtained.

We have previously made reference to the need of providing for accurate measurements of slight changes in load supplied to the network by the contributing stations, during the process of determining what adjustments should be made in load division between said contributing stations in order to ensure most economical overall system operation. We have also pointed out that close accuracy in determination of such small or incremental load changes (within a small percent of error in the measurement of the increment itself) necessarily corresponds to extremely small error of measurement when compared to the actual value of the load itself. Thus, when the incremental change amounts to, say, 5%, and

the required error in the measurement of the increment is 5% of such increment, the permissible error is only 0.25% of the load actually being supplied by the station whose load is being measured. Any suitable wattmeter or other power measuring instrument or device which is capable of measuring within the required accuracy at the load being carried may be used for the purposes of the present invention; but since it is doubtful that such instruments are available of a design and capacity which would meet the present requirements we now disclose an instrument which will fully meet such requirements as are imposed by the present equipment. For this purpose reference is now had to Figure 8 which shows, schematically, an incremental wattmeter suitable for the present purposes, and the following description thereof is now given:

The wattmeter shown in Figure 8 is what may be designated as a "suppressed zero" wattmeter. It is so arranged that normally it indicates the actual power being supplied over the lines to which it is connected, such power being read as the indication of a suitable pointer or needle working over a scale of suitable divisions and power indications. When, however, a small increment of power is to be read by the instrument, the circuits 20 may be temporarily modified by a suitable button or switch in such manner that the amount of the incremental value may be read in comparison to a suitable scale, conveniently another scale than that normally used, since the 25 incremental values are small, but are nevertheless spread over such scale of size approximating the size of the normally used scale. Upon depression of such button or actuation of such switch the circuit modifications may be adjusted so as to bring the pointer reading of the 30 instrument to zero position (prior to the incremental change), thus suppressing the instrument's zero reading; and then, while the circuits are still changed, and upon making the incremental change of power, the pointer of the instrument will show the value of such increment 35 by pointer swing over a range of the scale far larger than 40 would have been the pointer movement, had the instrument circuits not been modified. In other words, the circuit changes include provision for multiplying the pointer swing by a pre-determined multiplying factor. After the incremental value has been thus accurately determined, the circuits of the instrument will be restored 45 to their normal condition by releasing such button or restoring such switch to its normal position, the zero suppression being also discontinued. Specifically, the instrument shown in Figure 8 is as follows:

To measure power flowing in the circuit aa , the current I and the voltage E may be amplified by the amplifiers 114 and 115, respectively, the amplifier outputs supplying the current and voltage coils, respectively, of a wattmeter 116. If the amplifier gains are calibrated and the amplifiers have no phase shift error, the wattmeter indication will be

$$P = KEI \cos \theta$$

0 where K is a proportionality constant, and θ is the phase angle between E and I

The above described structure and method are well known and are frequently employed in network calculating tables and in other applications.

5 It is desired to measure a small increase in the power carried in the circuit *aa*. Such an increase may be small compared to the power carried in the circuit prior to the increase, and the increase in the indication of the wattmeter may not be accurately readable. To provide an accurate reading of a small increase in power the structure here described has been developed. It consists of the three vacuum tubes 117, 118 and 119, with associated circuit elements such as resistors and condensers, and a suitable supply of power for the necessary heater and 10 plate voltages.

Normally the output voltage of the transformer 120, which is proportional to the current I and in phase therewith, is impressed between the grid of tube 117 and ground; while the grid of the tube 118 is maintained effective at ground potential, the contacts of the push button 121 being open. Tube 117 acts as a conventional resistance coupled amplifier, resistor 122 being the load resistor, although of low gain value due to the parallel plate resistance of tube 118. The amplified output of tube 117, if the circuit is properly designed with established principles of resistance coupled amplifier design well known in the art followed, is a voltage which is substantially exactly proportional in magnitude to the magnitude of current I , and which is substantially exactly in phase with current I except for a possible deliberate reversal of phase in the polarity of transformer 120, as will be mentioned hereinafter. This voltage is impressed on the grid of amplifier 114, and, with proper adjustment of proportionality factors, results in an indication by the wattmeter of $P=KEI \cos \theta$, as previously described.

The voltage E of circuit aa is impressed on the voltage divider 123, and a predetermined fraction of E is impressed on the input grid of amplifier 115 and also on the grid of tube 119. Tube 119 is connected as a cathode follower, a form of amplifier having a gain of less than unity which is well known in the art. As is well known, the input impedance of the cathode follower grid is very high, approaching infinity at relatively low frequencies as may be employed in a network calculator. Hence, the connection of the grid of tube 119 does not measurably alter the voltage impressed on the input grid of amplifier 115. Tube 119, acting as a cathode follower, develops a voltage across its cathode resistor 124, which is substantially exactly proportional in magnitude to the magnitude of the voltage E , and substantially exactly in phase therewith. The cathode resistor 124 is shown as a potentiometer having a sliding contact connected, through the push button 121 and the condenser 125 for the purpose of blocking the direct current cathode voltage, to the grid of tube 118. By closing the contacts of the push button, and adjusting the position of the sliding contact of the potentiometer 124, a voltage in phase with and any desired fraction (between zero and an upper limit controlled by the circuit constants) of the magnitude of E , may be impressed on the grid of tube 118.

If the current I is zero, and the push button contacts are closed, tube 118 acts as a conventional resistance coupled amplifier, resistor 122 being the load resistor, and its output voltage is impressed on the input grid of amplifier 114. If polarity of the output of amplifier 114 is reversed with respect to its input, while that of amplifier 115 is not so reversed, the output of amplifier 114 is a voltage in phase opposition to E and adjustable in magnitude through movement of the sliding contact of the potentiometer 124. Under this condition, the wattmeter will indicate

$$P=-KE(1)$$

where K' is a constant depending upon the position of the sliding contact, (1) is the cosine of angle θ degrees, being the angle between E and the input to amplifier 114, and where the minus sign indicates the reversal of polarity through amplifier 114.

It should be noted that the reversal of polarity through amplifier 114 is normally counterbalanced by a similar reversal in polarity in the windings of transformer 120. It is also noted that, actually, the resistance coupled amplifiers comprised of the tubes 117 and 118 inherently introduce one polarity reversal each. This fact is disregarded here, since as both are reversed, the net effect on the wattmeter indication is zero.

If the current I assume some finite value within the range of magnitude contemplated in the design, both tube 117 and tube 118 act as resistance coupled ampli-

fiers, but as amplifiers having a common load resistor, 122. Neglecting for the moment certain secondary effects, the voltage developed across 122 will be the sum of the instantaneous voltages due to the plate currents of tubes 117 and 118. Keeping in mind the polarity reversal of transformer 120, the voltage developed across 122 by plate current of tube 117 will be

$$e_1=-KI/\theta$$

10 where $/\theta$ indicates that e_1 differs in phase from the voltage E by an angle θ ,

and the voltage developed across 122 by the plate current of tube 118 will be

$$e_2=K'E/0$$

where $/0$ indicates a zero phase difference between e_2 and E ,

15 and the voltage applied to the input grid of amplifier 114 will be

$$e=e_1+e_2=-KI/\theta+K'E$$

Recalling the phase reversal provided in amplifier 114, and with suitable correction for the gain of that amplifier, the output of amplifier 114 will be

$$e'=KI/\theta-K'E$$

and the wattmeter will indicate

$$P=E(KI/\theta-K'E)=KIE \cos \theta-K'E^2$$

30 Since K' is adjustable by the sliding potentiometer contact, the wattmeter indication may be adjusted to $P=0$ when the push button is closed; and is $P=KEI \cos \theta$, the true power, when the push button is open. If the gain of amplifier 114 is now changed from value G to value G' , the output of amplifier 114 changes in the same ratio to become

$$e'=G'/G(KI/\theta-K'E)$$

40 and the wattmeter will indicate

$$P=G'/G(KIE \cos \theta-K'E^2)=G'/(0)=0$$

if K' has been adjusted to produce a zero power reading before the amplifier gain was increased.

45 If, now, the current in circuit aa is caused to increase by a small increment dI/θ' , where $/\theta'$ may have any value not necessarily equal to $/\theta$, the voltage applied to the input grid of amplifier 114 becomes

$$e'=-KI/\theta-KdI/\theta'+K'E$$

and the output of amplifier 114 becomes

$$G'/G(KI/\theta+KdI/\theta'-K'E)$$

55 and the wattmeter indicates

$$P=G'/G(KEI \cos \theta+KEdI \cos \theta'-K'E^2)$$

This equals

$$P=G'/G(KEdI \cos \theta')$$

60 This is true since $KEI \cos \theta$ equals $K'E^2$ by adjustment.

Thus the wattmeter indicates the increment in power in circuit aa and at gain ratio of G'/G compared to the 65 indication of the larger power flow in the same circuit before increment.

The use of a plate load resistor in any resistance coupled amplifier produces a change in voltage applied at the plate as the grid voltage changes. The use of a 70 common load resistor impresses on the plate of each of tubes 117 and 118 a change in plate voltage due to the signal on the grid of the other. Using triodes and circuit constants normal for high gain, this circumstance would produce harmonic voltages in the combined output which 75 under the circumstances could produce errors in the watt-

meter indication. One method of reducing this secondary effect is to employ a relatively low value of load resistor, which is equivalent to a low gain. Since the output of the tubes 117 and 118 is amplified in amplifier 114, a very low gain at this point is not a disadvantage. Another and possibly more effective remedial measure is to employ pentode tubes as tubes 117 and 118 as the performance of pentodes is practically unaffected, over a reasonable range, by variations in plate voltage. Triodes are shown in Figure 8 as being simpler to describe and to explain, but it should be understood that pentodes will normally result in improved performance.

The equipment hereinbefore disclosed may be used to supply information concerning effects of change of distribution or division of total load between the several contributing stations, including the effects of such changes on losses in the various network elements, and including effects of incremental changes of loading supplied by each contributing station. It will be evident that said equipment may be used in various ways to secure desired information on the basis of which to effect solution of various problems related to load division and load distribution over the network. We have already pointed out the fact that changes in division of load between contributing stations, while maintaining the delivered loads at correct values of load, voltage, and power factor, effect changes in network losses, which in turn affect the total power required to be input by the contributing stations. The equipment herein disclosed may be used for study of all of these relationships and effects, and for facilitating solution of the basic problems involved in determining the most economical division of total power between the contributing stations. We do not limit ourselves to the use of such equipment according to any specified or particular procedure, nor to any specific method of solution of the basic problem of load division. Generally the information and data which may be secured by use of this equipment will be used for facilitating mathematical solution of various problems directly or indirectly related to such division of power. With the foregoing statement in mind we shall state hereunder one simple procedure which may be followed for determining a close solution of the problem of most economical load division, under network conditions frequently encountered.

A first approximation of the load division is made, based on the judgment and experience of the engineers, and using, if desired, such incremental rate curves of the various contributing stations as are generally shown in Figure 2. By this means a rather close approximation to the correct division may be made, taking into account the estimated losses, which losses are added to the useful delivered load on the network. The operator adjusts the load at each load center to correspond to the known conditions, and he divides both the real and the reactive loads among the contributing stations as his judgment indicates they should be divided for best overall performance. He checks the voltages at the load centers and makes such voltage adjustments at the contributing stations as may be necessary to bring all load center voltages within acceptable limits.

The operator then increases the load on one station by a small or incremental amount, by adjustment of the phase position of that station's output voltage, and reads from the wattmeters provided for the contributing stations, not only the incremental increase of the load thus increased on the one station, but also the decreases in output of the other contributing stations. In some cases, depending on the form of the network and the loads connected thereto, it may be known beforehand that increase at one station will not affect one or more of the loads on other stations, the effects being limited to one or two, only, of the other stations. Similar procedure is followed for each contributing station, the original conditions being restored at all of the stations, before proceeding to each succeeding station of the group.

The change in output for each of the above series of tests may be expressed

$$(I) \quad \Delta P_1, \Delta P_2, \dots, \Delta P_n$$

It can be shown by rigorous derivation that, with the net delivered loads remaining constant

$$(II) \quad dF_1\Delta P_1 + dF_2\Delta P_2 + \dots + dF_n\Delta P_n$$

is slightly greater than zero in the positive direction at optimum loading of station n (it being noted that $dF_1, dF_2, \dots, dF_n$ represent the incremental generating costs at the station buses). If the quantity is appreciably greater than zero, the station loading is greater than optimum; and if less than zero, the loading is less than optimum. The operation is repeated for all stations contributing to the network, and the loading of all of the stations is compared. An indication is thereby obtained of the necessary readjustment in each station. A number of tests may be conducted based on the above general procedure, until finally an acceptably close approximation to the exact division desired for most economical load division is obtained to meet the requirements.

It is not always possible to attain the theoretically most economical load division. It may be necessary to employ some portion of the capacity of some highly economical station to supply reactive in order to maintain voltage at some load center within acceptable limits, or any one of several other practical considerations may restrict the system to something less than the most economical division. The system operator, guided by the values determined according to the foregoing procedure, readjusts the division of both real and reactive power among the several stations, and by using the facilities hereinbefore disclosed, is able at once to determine whether or not the revised loading results in any voltage condition or other situation which would not be acceptable operating practice. If no such condition is indicated by the presently disclosed facilities, the operator makes a second series of readings and obtains a second series of values. These new values will show the extent of the improvement in hourly fuel cost which the re-division of loads has accomplished, and will indicate the amount and direction of any further re-division which may be desirable. The refinement to which these corrections will be carried is subject to the judgment of the operator, but he is always able to quickly check that judgment by reference to the present facilities. Furthermore, the system operator is able to completely duplicate the system performance under the conditions which he proposes to achieve before ordering any re-adjustment in either load or busbar voltage at any contributing station.

Another and very important use of the present facilities is in determination of power costs for billing purposes at interchange points where power is exchanged between separate systems. To this end it is possible to compute from the station operating costs and the line loss data, the cost of delivered power. Thus, the proposed delivered load, or the load as actually delivered, may be placed on the network at the proper point, and then a new solution for most economical generation of the total power may be made. Then a computation may be made from the generating station power cost and the line loss, of the cost of delivered power. The difference will obviously be the cost of delivering the proposed exchange power.

Another use of the present facilities is in computing the cost of power trunked for an interconnecting company from one point to another point on the system. The network may first be set up for the loads carried by the network, and the most economical generating schedule for the contributing stations may be determined. The system loss is also noted and the cost of delivered power is computed. The trunked power is then added to the network at one point and taken from the network

at the point of delivery. Then the most economical generation schedule for the contributing stations is determined and the system losses again noted. The total cost of power to the network owning system is then computed, and the difference between this amount and the cost when not trunking will be the true cost of trunking the power through the network.

The foregoing illustrations will briefly indicate some of the beneficial uses of the facilities hereinbefore disclosed. Many other useful applications of said facilities will be evident to users of such equipment.

We claim:

1. A calculating table including in combination a plurality of sections to simulate real network sections, and means to connect said simulating sections together to simulate the real network, together with means to determine and give a direct indication of power loss occurring in at least one network section due to current flow through said network section, at least said network section including a resistance element, simulating network connections to said resistance element, current supply connections to said network for flow of current through the network sections including said section which includes a resistance element, said simulating network connections being constituted for flow of substantially the full current of such section through said resistance element to cause potential drop across said resistance element substantially proportionate to the full current flow through such network section, together with means to translate the drop of potential across said resistance element into a difference of D. C. potential which is proportional to the squared value of said drop of potential across said resistance element, and means to give an indication of power loss proportional to said difference of D. C. potential.

2. Means as specified in claim 1, wherein said means to translate the drop of potential across the resistance element into a difference of D. C. potential which is proportional to the squared value of the drop of potential across the resistance element includes a transformer, together with connections between the resistance element and the primary of such transformer, the potential across the primary of said transformer being substantially proportional to the current flowing through the network section to which said transformer corresponds, and rectifying means between the power loss indication giving means and the secondary of the transformer.

3. Means as specified in claim 2, wherein the primary and secondary of said transformer are insulated from each other.

4. Means as specified in claim 3, wherein each of a plurality of the simulating network sections is provided with a resistance element, and a transformer having a primary, and connections between each resistance element of a section and the primary of the transformer corresponding thereto, and wherein each of said plurality of the simulating network sections is provided with means to translate the drop of potential across its resistance element into a difference of D. C. potential which is proportional to the squared value of the drop of potential across its resistance element, together with connections to summarize said differences of D. C. potential for said plurality of sections, and means to give an indication of the summation of said differences of D. C. potential for said plurality of sections.

5. Means as specified in claim 4, wherein said plurality of simulating network sections includes all of the simulating network sections of the calculating table.

6. Means as specified in claim 1, wherein the means to translate the drop of potential across the resistance element into a difference of D. C. potential which is proportional to the squared value of said drop of potential across said resistance element, includes varistor current rectifying means.

7. A calculating table including in combination a plurality of sections to simulate real network sections, and means to connect said simulating sections together to simulate the real network, and current supply connections for flow of current through the network sections of the calculating table, each section including impedance simulating means to simulate the impedance of the corresponding real network section, and also including means responsive to the current flow through such section to produce a difference of D. C. potential which is proportional to the power loss occurring in such section due to current flow through such section.

8. Means as specified in claim 7, wherein said means which is responsive to the current flow through each simulating network section to give an indication proportionate to the power loss due to the current flowing through such section includes a power loss determination circuit element electrically independent of the simulating network sections, together with terminals for said power loss determination circuit element, and wherein the difference of D. C. potential between the terminals of each power loss determination circuit element is linearly proportionate to the power loss due to the current flow through such section of the simulating network.

9. Means as specified in claim 8, together with an indicating device to indicate power loss, and connections between the terminals of the power loss determination circuit elements of selected simulating network sections and said indicating device, including means to cause the indicating device to give its indication proportionally to the summation of the D. C. potentials across the terminals of the power loss determination circuit elements of said selected simulating network sections.

10. Means as specified in claim 9 wherein said indicating device comprises an instrument of the multi-range D. C. voltmeter type and includes means to select the range on which said instrument gives its indications, together with means to introduce into said series circuit an opposing D. C. potential of selected amount.

11. Means as specified in claim 10, wherein the said opposing D. C. potential is adjustable to an amount to balance the series additive circuit potential corresponding to a selected loading of the simulating network.

12. A calculating table including in combination a plurality of sections to simulate real network sections, and means to connect said simulating sections together to simulate the real network, together with means to determine and give a direct indication of power loss occurring in at least one network section due to current flow through said network section, at least said network section including a resistance element, simulating network connections to said resistance element, A. C. current supply connections to said network for flow of current through the network sections including said section which includes a resistance element, said simulating network connections being constituted for flow of substantially the full current of such section through said resistance element to cause potential drop across said resistance element substantially proportionate to the full current flow through such network section, together with means to translate the drop of potential across said resistance element into a difference of D. C. potential which is proportional to the squared value of said drop of potential across said resistance element, and means to give an indication of power loss proportional to said difference of D. C. potential, wherein the simulating network current flowing in said section is an alternating current supplied between said A. C. current supply connections and the drop across said resistance element is an A. C. potential difference, and wherein the means to translate said drop of potential across said resistance element into a difference of D. C. potential which is proportional to the squared value of said drop of A. C. potential across said resistance element includes a rectify-

75

ing element of the varistor type, a pair of D. C. terminals, means and connections between the resistance element and said D. C. terminals to produce a difference of D. C. potential between said terminals, said means including at least one such varistor element having the characteristic that the value of the current flow through said varistor element is substantially proportional to the square of the value of the A. C. potential imposed on said varistor element through a limited range of said A. C. potential values, and a loading resistor element in connection with said terminals to absorb current flow delivered through said varistor element, the D. C. potential between said terminals being proportional to the current flow through said loading resistance element as permitted by said varistor element.

13. Means as specified in claim 12, wherein the means to translate the drop of A. C. potential across said resistance element into a difference of D. C. potential which is proportional to the squared value of said A. C. potential impressed across said resistance element includes a plurality of rectifying elements of the varistor type and connections between the points of A. C. potential difference and said plurality of varistors, and between said plurality of varistors and the D. C. terminals, comprising a full wave rectifying unit including said varistors, wherein each branch of said full wave rectifying unit includes at least one of said varistors.

14. Means as specified in claim 13, wherein each branch of said full wave rectifying unit includes a plurality of said varistors together with connections between said varistors, said connections being constituted to establish a series circuit in each branch of said rectifying unit, the series circuit in each branch including the varistors of said branch and being constituted to permit current flow in a given direction, only, in said branch.

15. Means as specified in claim 14, together with another varistor and a resistor for each branch of the full wave rectifying unit, and connections for said other varistor and resistor of such branch, said connections being constituted to establish a series circuit including the varistor and the resistor of such branch, and to connect such series circuit in parallel connection with the series circuit of said branch which series circuit includes the plurality of varistors, one of said circuits including a plurality of varistors in series with each other and the other of said circuits including a varistor and a resistor in series with each other, and both of said circuits which include the varistor means permitting current flow through said branch in the same direction, only.

16. Means as specified in claim 12, wherein the means to translate said drop of potential across said resistance element into a difference of D. C. potential which is proportional to the squared value of said A. C. potential which is impressed across said resistance element includes a rectifying unit including a plurality of rectifying elements of the varistor type, and connections between said varistor type rectifying elements and the points of A. C. potential difference, said connections being constituted to establish a series circuit including said plurality of varistor elements permitting current flow in a given direction, only, between said points of A. C. potential difference.

17. Means as specified in claim 16, together with another rectifying element of the varistor type and a resistor, and connections to place said varistor and said resistor in series circuit with each other, and connections between the terminals of said series circuit and the terminals of the series circuit which includes the plurality of varistor elements, to thereby establish parallel circuits between the points of A. C. potential difference, one of said circuits including the plurality of varistors in series with each other and the other of said circuits including the varistor and the resistor in series with each

other, and both of said circuits including varistor means permitting current flow through said branch in the same direction, only.

18. A calculating table for use in the analysis of the effects produced on total cost of supply of power to load demands on a network produced by change of distribution of the total current supply to said network among a plurality of contributors of power to such network, said calculating table including in combination a plurality of sections to simulate real network sections, and means to connect said simulating sections together to simulate the real network, each section including impedance simulating means to simulate the impedance of the corresponding real network section and including means to adjust the impedance of such section, a plurality of connections for input of current to said network at selected points of said network, means to adjust the value of current input by each of said connections, and power metering means in conjunction with each current input connection aforesaid, each of said power metering means including a movable power indicating element and also including means under control of the operator to change the amount of movement of the movable power indicating element per unit change of power in the current input connection to which said power metering means corresponds.

19. Means as specified in claim 18, wherein there is means under control of the operator to cause the indicating element of the power metering means to read at the zero power indicating position for an established value of current flow through the corresponding current input connection to the network.

20. A calculating table for use in the analysis of the effects produced on total cost of supply of power to load demands on a network produced by change of distribution of the current supply to said network among a plurality of contributors of power to such network, said calculating table including in combination a plurality of sections to simulate real network sections, and means to connect said simulating sections together to simulate the real network, each section including impedance simulating means to simulate the impedance of the corresponding real network section and including means to adjust the impedance of such section, a plurality of connections for input of current to said network at selected points of said network, means to adjust the value of current input by each of said connections, and power metering means in conjunction with each current input connection aforesaid, each of said power metering means including a movable power indicating element and also including means under control of the operator to cause the indicating element of the power metering means to read at the zero power indicating position for an established value of current flow through the corresponding current input connection to the network.
